UNITED STATES PATENT OFFICE.

GEORGE E. PANCOAST, OF NEW YORK, N. Y., ASSIGNOR TO THE AMERICAN LITHOGRAPHIC COMPANY, OF NEW YORK.

PRINTING-PRESS.

SPECIFICATION forming part of Letters Patent No. 659,351, dated October 9, 1900.

Application filed March 6, 1900. Serial No. 7,447. (No model.)

To all whom it may concern:

Be it known that I, GEORGE E. PANCOAST, a citizen of the United States, and a resident of the city of New York, (Brooklyn,) county 5 of Kings, and State of New York, have invented certain new and useful Improvements in Printing-Presses, of which the following is a specification.

This invention relates to mechanism adapted and designed for use in making printing-surfaces, and which is of special utility in making curved and cylindrical printing-surfaces. Prior to my invention many difficulties have been encountered in the lithographic art in making curved or cylindrical printing-surfaces, especially when such surfaces are intended to print in proper register. The only practical solution of the problem yet proposed has been by employing 15 rolling contact between a printing-form and a basic surface, whereby the transfers of the latter are imposed upon the former. The present invention accomplishes the desired result without employing rolling contact and 20 by mechanism which combines efficiency with economy and simplicity. The invention is addressed to that department of the art usually termed "transferring." It will of course be understood that although the printing-form is a plane surface to start with it may in its development result in a planographic, relief, or intaglio printing-surface.

In the accompanying drawings, forming part of this specification and illustrating one 25 embodiment of the invention and one modification thereof, Figure 1 is a front elevation, partly in section, of a machine embodying the invention. Fig. 2 is an end elevation looking toward the left of Fig. 1. Fig. 3 is 30 a sectional elevation on the line 3 3 of Fig. 1. Fig. 4 is a front elevation of the left end of a clamping device. Fig. 5 is a rear elevation of the right end of the clamping device. Fig. 6 is a sectional elevation on the line 6 6 35 of Fig. 5. Fig. 7 is a fragmental front elevation of a modification, and Fig. 8 is a sectional elevation on the line 8 8 of Fig. 7.

Referring now to the specific construction of the devices in the drawings, 1 is a cylindrical form-support having trunnions 2 and 3 and removably mounted in bearings in the

main frame of the machine and held against rotation by the key 4. The form-support has a shoulder 5 at one end and adjustable clamps 6 at the other end. 55

7 is a removable and replaceable printing-form adapted to have a design imposed thereon and to be developed into a printing-surface of the character desired—planographic, relief, or intaglio. It is preferably a hollow 60 cylindrical shell, as shown, and when seated in place on its support fits accurately against the shoulder 5, against which it is held by the clamps 6.

8 is a revolving pressure device consisting 65 of the cross-piece 9 and the arm 10 and the arms 11 12, these arms being pivotally hung from the shaft 2.

For the purpose of removing and replacing the printing-surface one side of the main 70 frame has a hinged portion 13, which is adapted to be turned down out of the way. This hinged portion 13 is provided with a locking-bar 14 and is designed to carry the box 15, in which rests the trunnion 3. 75

16 is a nut which screws on the end of the trunnion 3 on the outside of the hinged piece 13, so as to hold this piece 13 firmly in upright position when the printing-form is in place on its support. The locking-bar 14 extends 80 across the top of the box 15 and is secured in place by the nut 17, so as to hold the box 15 firmly in place. The arms 11 and 12 are pivoted to the cross-piece 9 by the bolt 18, so as to be capable of being disengaged from the 85 trunnion 3. Pivoted on the arm 12 is a locking-bar 19, which is adapted to enter a recess in the upper end of the arm 11 and by means of the nut 20 lock the arms 11 and 12 together 90 in engagement with the trunnion 3. This arrangement of the arms 11 and 12 is designed merely as a convenient arrangement to facilitate the removal of a printing-form. When the printing-form is to be removed, the bar 19 is unlocked and thrown back, and the arms 95 11 and 12 are separated and disengaged from the trunnion 3. The bar 14 is then unlocked and thrown back, the nut 16 is removed, and the hinged piece 13 turned down into the position shown in dotted lines in Fig. 1. An 100 arm is generally brought into alignment with and locked with the trunnion 3, and upon it

the printing-form 7 may be slid from the form-support. This arm, which is not shown, may operate to support the trunnion 3; but generally the form-support 1 will be sufficiently supported by the trunnion 2 at the opposite side of the frame. In removing a printing-form the clamps 6 are loosened and turned inward, so that the printing-form may be slipped from its support. The collar 5 insures the seating of the printing-form always in the same exact predetermined longitudinal position. The exact predetermined transverse or circumferential position of the printing-form on its support is insured by the rib 21 on the inner side of the printing-form, which enters a corresponding groove in the form-support. Other means, of course, may be employed for this purpose.

The revolving pressure device 8 is provided with a yielding scraper 22, which rests in a slot in the cross-piece 9 and is pressed radially toward the periphery of the printing-form by springs 23. These springs have screws 23^a by which to adjust their tension. The basic surface 24, which is non-expansible and non-contractible, has a design or a plurality of designs affixed thereto, so as to be non-expansible and non-contractible. The basic surface is flexible and generally consists of a flexible sheet of metal, preferably a thin sheet of steel, having one or two layers of paper affixed thereto and upon which is stuck up in proper position the various transfer-sheets whose designs are to be imposed upon the printing-form. One end of the basic surface is secured in a suitable holding device, which may be a clamping device, such as shown. This clamping device consists of a bar 25, whose ends are bolted to the inner sides of the main frame, and a removable bar 26, adapted to be clamped against the bar 25 by the screws 27. The clamp end of the basic surface is turned down, as shown in Fig. 6, and is provided with a row of perforations 28, which fit accurately over the pins 29, secured on the bar 25. The pins 29 and perforations 28 insure the exact longitudinal and transverse position of the basic surface. Other means, of course, may be employed for this purpose.

In the modifications shown in Figs. 7 and 8 the same construction is shown, with the exception of the revolving pressure device. In Figs. 7 and 8 the pressure device 30 is revolvably connected with the trunnions 2 and 3 by the arms 10, 11, and 12, but is provided with a roller 31 instead of a scraper 22, as shown in Figs. 1, 2, 3, and 4. The roller 31 is supported in boxes 32, carried by the cross-piece 33, and has springs 34 to yieldingly press the roller radially against the periphery of the printing-form 7.

35 are screws to adjust the tension of the springs 34.

65 In the operation of the machine the pressure device 8 is revolved around the printing-

form and bears against the outer side of the flexible basic surface, pressing it by scraping contact radially inward against the periphery of the printing-form, and thereby imposing 70 the designs of the basic surface upon the printing-form, these designs being thus located in a precise predetermined position both longitudinally and transversely upon the printing-form. During the revolution of the 75 pressure device the printing-form is held against rotation, and thus is stationary. It will be understood, however, that it is not essential that the printing-form be entirely and at all times immovable or stationary. For example, the printing-form might be held immovable or stationary while the pressure device is revolved through a short arc to impose the design or designs upon a portion of the periphery of the printing-form. Then the 80 basic surface and printing-form may be moved backward through this same arc, with the pressure of the presser device removed. Then the printing-form may be locked again immovably in place and the pressure device 90 revolved through the same short arc to impose another portion of the designs upon the printing-form, as before. This same operation may be repeated until every portion of the designs has been imposed upon the printing-form. The operation of the pressure device 30 is the same as that of the device 8, except that in the former the roller 31 rolls over the outer surface of the basic surface instead of scraping over it. The printing-form may 95 be a curved shell or it may be a complete cylindrical shell adapted to be supported on a form-support in the manner shown in the drawings, or it may be a solid curved or cylindrical body or a hollow curved or cylindrical shell-like body of such thickness as to require no separate form-support. It is preferably, but not essentially, a complete cylinder.

Some of the advantages of this invention 110 may be attained in imposing designs upon a flexible printing-form from a curved or cylindrical basic surface. To accomplish this result, a curved or cylindrical basic surface may be mounted on the main frame in the 115 same way as the printing-form 7, and a flexible printing-form, which may be made of zinc, aluminium, or other suitable material, may be arranged in the same way as the basic surface 24. The revolving pressure device would 120 then press the flexible printing-form into contact with the stationary basic surface in the same way as the basic surface 24 is pressed into contact with the printing-form 7.

It will be understood that various other 125 changes in the form and arrangement may be made without departing from the scope of the invention.

While the invention is applicable to the art 130 of making printing-surfaces, whether lithographic or planographic, intaglio or relief when developed, and is an improvement in

such art, it is of special advantage in the art of making lithographic or planographic printing-surfaces.

What I claim as new, and desire to secure
5 by Letters Patent, is—

1. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving pressure device arranged to revolve around the said curved body while simultaneously bearing upon the said flexible body on its outer side and pressing it radially against said curved body, whereby the design or designs of the basic surface are progressively imposed upon the printing-form.
2. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving yielding pressure device arranged to revolve around the said curved body while simultaneously bearing upon the said flexible body on its outer side and pressing it radially against said curved body, whereby the design or designs of the basic surface are progressively imposed upon the printing-form.
3. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving scraper arranged to revolve around the said curved body while simultaneously bearing upon the said flexible body on its outer side and pressing it radially against said curved body, whereby the design or designs of the basic surface are progressively imposed upon the printing-form.
4. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving pressure device arranged to revolve around the said curved body while simultaneously bearing upon the said flexible body on its outer side and pressing it radially against said curved body, whereby the design or designs of the basic surface are progressively imposed upon the printing-form.

tible; a suitable printing-form adapted to have a design imposed upon it and to be thereafter developed into a printing-surface, one of said bodies being flexible and the other curved; and means for bringing said bodies together in progressive transferring contact, said means including a revolving yielding scraper arranged to revolve around the said curved body while simultaneously bearing upon the said flexible body on its outer side and pressing it radially against said curved body, whereby the design or designs of the basic surface are progressively imposed upon the printing-form. 70 75 80

5. In a machine for making printing-surfaces, the combination of a suitable non-expansible and non-contractible basic surface having fixed thereto a design or designs so that the design is non-expansible and non-contrac-
85
tible; a suitable printing - form adapted to have a design imposed upon it and to be there-
after developed into a printing-surface, one of said bodies being flexible and the other 90
curved; means for holding one end of the flexible body in fixed position, and means for bringing said bodies together in progressive transferring contact, said means including a revolving pressure device arranged to revolve 95
around the said curved body while simulta-
neously bearing upon the said flexible body on its outer side and pressing it radially against said curved body, whereby the design or designs of the basic surface are progress-
900
ively imposed upon the printing-form.

6. In-a machine for making printing-surfaces, the combination of a suitable non-expansible and non-contractible basic surface having fixed thereto a design or designs so that the design is non-expansible and non-contractible; a suitable printing - form adapted to have a design imposed upon it and to be thereafter developed into a printing-surface, one of said bodies being flexible and the other curved; a holding device carried by the frame of the machine and adapted to engage one end of the flexible body and hold it in fixed position; and means for bringing said bodies together in progressive transferring contact, said means including a revolving pressure device arranged to revolve around the said curved body while simultaneously bearing upon the said flexible body on its outer side and pressing it radially against said curved body, whereby the design or designs of the basic surface are progressively imposed upon the printing-form. 110 115 120

7. In a machine for making printing-surfaces, the combination of a suitable non-expansible and non-contractible basic surface having fixed thereto a design or designs so that the design is non-expansible and non-contractible; a suitable printing - form adapted to have a design imposed upon it and to be thereafter developed into a printing-surface, one of said bodies being flexible and the other curved, a clamping device carried by the main frame of the machine and adapted to engage

one end of the flexible body and hold it fixed in position; and means for bringing said bodies together in progressive transferring contact, said means including a revolving 5 pressure device arranged to revolve around the said curved body while simultaneously bearing upon the said flexible body on its outer side and pressing it radially against said curved body, whereby the design or designs 10 of the basic surface are progressively imposed upon the printing-form.

8. In a machine for making printing-surfaces, the combination of a suitable non-expansible and non-contractible basic surface 15 having fixed thereto a design or designs so that the design is non-expansible and non-contractible; a suitable printing-form adapted to have a design imposed upon it and to be thereafter developed into a printing-surface, 20 one of said bodies being flexible and the other curved; means for holding one end of the flexible body in fixed position; and means for bringing said bodies together in progressive transferring contact, said means including a revolving 25 yielding-pressure device arranged to revolve around the said curved body while simultaneously bearing upon the said flexible body on its outer side and pressing it radially against said curved body, whereby the 30 design or designs of the basic surface are progressively imposed upon the printing-form.

9. In a machine for making printing-surfaces, the combination of a suitable non-expansible and non-contractible basic surface 35 having fixed thereto a design or designs so that the design is non-expansible and non-contractible; a suitable printing-form adapted to have a design imposed upon it and to be thereafter developed into a printing-surface, 40 one of said bodies being flexible and the other curved; means for holding one end of the flexible body in fixed position; and means for bringing said bodies together in progressive transferring contact, said means including a revolving 45 scraper arranged to revolve around the said curved body while simultaneously bearing upon the said flexible body on its outer side and pressing it radially against said curved body, whereby the design or 50 signs of the basic surface are progressively imposed upon the printing-form.

10. In a machine for making printing-surfaces, the combination of a suitable non-expansible and non-contractible basic surface 55 having fixed thereto a design or designs so that the design is non-expansible and non-contractible; a suitable printing-form adapted to have a design imposed upon it and to be thereafter developed into a printing-surface, 60 one of said bodies being flexible and the other curved; a holding device carried by the frame of the machine and adapted to engage one end of the flexible body and hold it in fixed position; and means for bringing said bodies together in progressive transferring contact, said means including a revolving 65 scraper arranged to revolve around the said

curved body while simultaneously bearing upon the said flexible body on its outer side and pressing it radially against said curved body, whereby the design or designs of the basic surface are progressively imposed upon the printing-form. 70

11. In a machine for making printing-surfaces, the combination of a suitable non-expansible and non-contractible basic surface 75 having fixed thereto a design or designs so that the design is non-expansible and non-contractible; a suitable printing-form adapted to have a design imposed upon it and to be thereafter developed into a printing-surface, 80 one of said bodies being flexible and the other curved; a clamping device carried by the main frame of the machine and adapted to engage one end of the flexible body and hold it in fixed position; and means for bringing 85 said bodies together in progressive transferring contact, said means including a revolving yielding scraper arranged to revolve around the said curved body while simultaneously bearing upon the said flexible body on its outer side and pressing it radially against said curved body, whereby the design or designs of the basic surface are progressively imposed upon the printing-form. 90

12. In a machine for making printing-surfaces, the combination of a suitable non-expansible and non-contractible basic surface 95 having fixed thereto a design or designs so that the design is non-expansible and non-contractible; a suitable printing-form adapted to have a design imposed upon it and to be thereafter developed into a printing-surface, 100 one of said bodies being flexible and the other curved; and means for bringing said bodies together in progressive transferring contact, said means including a revolving pressure device arranged to revolve around the said curved body while simultaneously bearing upon the said flexible body on its 105 outer side and pressing it radially against said curved body, whereby the design or designs of the basic surface are progressively imposed upon the printing-form, and pre-established guides whereby said design or 110 designs may be imposed upon the printing-form in exact predetermined position both longitudinally and transversely. 115

13. In a machine for making printing-surfaces, the combination of a suitable non-expansible and non-contractible basic surface 120 having fixed thereto a design or designs so that the design is non-expansible and non-contractible; a suitable printing-form adapted to have a design imposed upon it and to be thereafter developed into a printing-surface, 125 one of said bodies being flexible and the other curved; a support for said curved body from which it is removable and replaceable; pre-established guides whereby said curved 130 body may be mounted in exact predetermined position both longitudinally and transversely; means for holding one end of the flexible body in fixed position; pre-established guides where-

by said flexible body may be held in exact predetermined position both longitudinally and transversely; and means for bringing said bodies together in progressive transferring contact, said means including a revolving pressure device arranged to revolve around the said curved body while simultaneously bearing upon the said flexible body on its outer side and pressing it radially against said curved body, whereby the design or designs of the basic surface are progressively imposed upon the printing-form in exact predetermined position.

14. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving yielding pressure device arranged to revolve around the said curved body while simultaneously bearing upon the said flexible body on its outer side and pressing it radially against said curved body, whereby the design or designs of the basic surface are progressively imposed upon the printing-form, and pre-established guides whereby said design or designs may be imposed upon the printing-form in exact predetermined position both longitudinally and transversely.

15. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; and means for bringing said bodies together in progressive transferring contact, said means including a revolving scraper arranged to revolve around the said curved body, while simultaneously bearing upon the said flexible body on its outer side and pressing it radially against said curved body, whereby the design or designs of the basic surface are progressively imposed upon the printing-form, and pre-established guides whereby said design or designs may be imposed upon the printing-form in exact predetermined position both longitudinally and transversely.

16. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface,

face, one of said bodies being flexible and the other curved; means for holding one end of the flexible body in fixed position; and means for bringing said bodies together in progressive transferring contact, said means including a revolving pressure device arranged to revolve around the said curved body while simultaneously bearing upon the said flexible body on its outer side and pressing it radially against said curved body, whereby the design or designs of the basic surface are progressively imposed upon the printing-form, and pre-established guides whereby said design or designs may be imposed upon the printing-form in exact predetermined position both longitudinally and transversely.

17. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; a holding device carried by the frame of the machine and adapted to engage one end of the flexible body and hold it in fixed position; and means for bringing said bodies together in progressive transferring contact; said means including a revolving pressure device arranged to revolve around the said curved body while simultaneously bearing upon the said flexible body on its outer side and pressing it radially against said curved body, whereby the design or designs of the basic surface are progressively imposed upon the printing-form, and pre-established guides whereby said design or designs may be imposed upon the printing-form in exact predetermined position both longitudinally and transversely.

18. In a machine for making printing-surfaces, the combination of a suitable non-expansible and non-contractible basic surface having fixed thereto a design or designs so that the design is non-expansible and non-contractible; a suitable printing-form adapted to have a design imposed upon it and to be thereafter developed into a printing-surface, one of said bodies being flexible and the other curved; a support for said curved body from which it is removable and replaceable; pre-established guides whereby said curved body may be mounted in exact predetermined position both longitudinally and transversely; means for holding one end of the flexible body in fixed position; pre-established guides whereby said flexible body may be held in exact predetermined position both longitudinally and transversely; and means for bringing said bodies together in progressive transferring contact, said means including a revolving yielding pressure device arranged to revolve around the said curved body while simultaneously bearing upon the said flexible body on its outer side and pressing it radially

against said curved body, whereby the design or designs of the basic surface are progressively imposed upon the printing-form.

19. In a machine for making printing-surfaces, the combination of a suitable non-expansible and non-contractible basic surface having fixed thereto a design or designs so that the design is non-expansible and non-contractible, said basic surface comprising a flexible sheet; a suitable curved or cylindrical printing-form adapted to have a design imposed upon it and to be thereafter developed into a printing-surface; and means for bringing said bodies together in progressive transferring contact, said means including a revolving pressure device arranged to revolve around said printing-form while simultaneously bearing upon said flexible basic surface on its outer side and pressing it radially against the printing-form, whereby the design or designs of the basic surface are progressively imposed upon the printing-form.

20. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical printing-form adapted to have a design imposed upon it and to be thereafter developed into a printing-surface, and means for bringing said bodies together in progressive transferring contact, said means including a revolving yielding pressure device arranged to revolve around said printing-form while simultaneously bearing upon said flexible basic surface on its outer side and pressing it radially against the printing-form, whereby the design or designs of the basic surface are progressively imposed upon the printing-form.

21. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical printing-form adapted to have a design imposed upon it and to be thereafter developed into a printing-surface; and means for bringing said bodies together in progressive transferring contact, said means including a revolving scraper arranged to revolve around said printing-form while simultaneously bearing upon said flexible basic surface on its outer side and pressing it radially against the printing-form, whereby the design or designs of the basic surface are progressively imposed upon the printing-form.

22. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical

printing-form adapted to have a design imposed upon it and to be thereafter developed into a printing-surface; means for holding one end of the basic surface in fixed position; and means for bringing said bodies together in progressive transferring contact, said means including a revolving pressure device arranged to revolve around said printing-form while simultaneously bearing upon said flexible basic surface on its outer side and pressing it radially against the printing-form, whereby the design or designs of the basic surface are progressively imposed upon the printing-form.

23. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical printing-form adapted to have a design imposed upon it and to be thereafter developed into a printing-surface, a holding device carried by the frame of the machine and adapted to engage one end of the basic surface and hold it in fixed position; and means for bringing said bodies together in progressive transferring contact, said means including a revolving pressure device arranged to revolve around said printing-form while simultaneously bearing upon said flexible basic surface on its outer side and pressing it radially against the printing-form, whereby the design or designs of the basic surface are progressively imposed upon the printing-form.

24. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical printing-form adapted to have a design imposed upon it and to be thereafter developed into a printing-surface, and means for bringing said bodies together in progressive transferring contact; said means including a revolving pressure device arranged to revolve around said printing-form while simultaneously bearing upon said flexible basic surface on its outer side and pressing it radially against the printing-form, whereby the design or designs of the basic surface are progressively imposed upon the printing-form, and preestablished guides whereby said design or designs may be imposed upon the printing-form in exact predetermined position both longitudinally and transversely.

25. In a machine for making printing-surfaces, the combination of a suitable non-expansible and non-contractible basic surface having fixed thereto a design or designs so that the design is non-expansible and non-contractible; said basic surface comprising a flexible sheet; a suitable curved or cylindrical printing-form adapted to have a de-

sign imposed upon it and to be thereafter developed into a printing-surface; a support for said printing-form from which it is removable and replaceable; preëstablished 5 guides whereby said printing-form may be mounted in exact predetermined position both longitudinally and transversely; means for holding one end of the basic surface in fixed position; preëstablished guides where- 10 by said basic surface may be held in exact predetermined position both longitudinally and transversely; and means for bringing said bodies together in progressive transfer- 15 ring contact, said means including a revolving pressure device arranged to revolve

around said printing-form while simultane- 20 ously bearing upon said flexible basic sur- face on its outer side and pressing it radi- ally against the printing-form, whereby the design or designs of the basic surface are progressively imposed upon the printing- form.

In testimony whereof I have signed my name to this specification in the presence of two subscribing witnesses.
